UNITED STATES PATENT OFFICE.

HARRY W. MACDOUGALL, OF EAST ORANGE, NEW JERSEY, ASSIGNOR TO WESTERN ELECTRIC COMPANY, INCORPORATED, OF NEW YORK, N. Y., A CORPORATION OF NEW YORK.

TESTING SYSTEM FOR AUTOMATIC TELEPHONE SWITCHES.

Application filed December 8, 1923. Serial No. 679,314.

This invention relates to a telephone exchange system and more particularly to a testing device in a machine switching system for testing selector switch units.

5 It is an object of this invention to provide an improved testing system.

The switching units of an automatically operated telephone exchange are made up of control apparatus, relays and auxiliary 10 circuits to control its automatic progression and further control other switching units. A large number of such switching units are required in a system of this kind, any 15 one of which may be arbitrarily selected, when idle, to complete a service connection. Thus, it is apparent that a switching unit giving inefficient service is not immediately noticed. Since the apparatus of a switching unit requires adjustments within limited 20 variations, it is important that these units be regularly tested to determine their ability to render efficient service. In order to reduce the cost of such maintenance, it is desirable to use a testing system requiring 25 a limited amount of manual operation.

A feature of this invention is in the use of a common testing device.

A further feature of this invention resides in the provision of means for determining 30 whether the brushes associated with the automatic switches are in contact with the terminals to which they have been directed.

A still further feature of this invention is found in the use of a testing device to 35 determine whether or not the conductors of an automatic switch are short-circuited or grounded.

Another feature of this invention is the provision of a testing device equipped with 40 keys to function as the register of a sender, in combination with a progression switch, to automatically control the connection of a selector switch to either a test line or a subscriber's line switch. The testing device 45 remains positioned in such a manner as to receive a signal upon the completion of the tests.

These and other features of the invention 50 will be apparent from the following description taken in connection with the accompanying drawings.

While the invention has been disclosed as particularly adapted for testing switches of the panel type, it will be apparent from

the following description that the invention 55 has a wider utility and that by slight modifications it could be adapted for testing other types of selector switches.

Figs. 1 and 2 show a testing and controlling circuit for directing the incoming selector switch and the final selector switch 60 to either a test line or a subscriber's line.

Fig. 3 shows the incoming selector switch to be tested.

Fig. 4 shows a final selector switch to be 65 tested and to be connected to the wanted line.

Fig. 5 shows a line switch circuit associated with the subscriber's station. It is in all respects similar to that shown in Fig. 70 1 of Patent No. 1,395,977, issued November 1, 1921 to F. A. Stearn and F. J. Scudder.

The key set shown in Fig. 1 is made up of mechanically locking keys. The switch shown in Fig. 2 is of a well known step-by-step type.

The automatic selector switches shown in Figs. 3 and 4 are of the well known power driven type in which a plurality of sets of brushes are mounted on a vertical brush 80 shaft and arranged to be selectively tripped into engagement with individual terminal banks. The brush shafts are propelled in a vertical direction by means of constantly rotating power drums. In general construction and operation these switches are both of the same character as the one shown and described in detail in Patent No. 1,123,696, issued January 5, 1915, to E. B. Craft and J. N. Reynolds. More specifically, the incoming selector shown in Fig. 3 and the final selector shown in Fig. 4 are described in the above mentioned patent to F. A. Stearn, et al. 90

The test man before proceeding with the test on an incoming selector inserts plug 234 95 into jack 304 and plug 232 into jack 231. Certain of keys 130 to 169 are then depressed to register the line number to which the selector switch is to be directed. A start key is then actuated by the test man and 100 from this point the operation is automatic until trouble is encountered or a signal is received by the test man that the test has been successfully completed.

Upon the actuation of the start key, a 105 progressively operated switch is actuated and in its progressive movement, establishes circuits for directing the incoming selector

switch to a particular final selector switch and the final selector switch to a group of terminals which have been made busy by the insertion of a plug in a multiple 5 jack associated therewith.

The incoming selector switch performs its usual functions when the busy line is encountered, that is, it provides a path over which a busy flash may be sent to the test 10 circuit. Upon the reception of this flash, the test man is in a position to know that the test has been successfully completed.

A test may be made on the final selector switch shown in Fig. 4 by the insertion of 15 plug 234 in jack 453 and the actuation of certain of keys 130 to 169 to direct the final selector switch to any subscriber's line. The successful completion of the test is indicated by the operation of a relay in a circuit whose 20 battery and ground are supplied from the line circuit.

Having now described in a general way the apparatus employed in conducting tests and the manner in which it is to be used, 25 it is thought that the invention will be better understood by a consideration of the specific manner in which it functions.

Brush continuity test of incoming selector.

30 To initiate the test, plug 232 is inserted into jack 231, plug 234 is inserted into jack 304 of the particular selector circuit to be tested, and plug 444 is inserted into jack 445, the purpose of which is hereinafter 35 described. The proper keys, shown in Fig. 1, to control the incoming and final selector switches to select a line will then be depressed. Assuming that the line to be selected is 3190, keys 133, 141, 159 and 160 will be 40 actuated. The actuation of the above designated keys will associate certain of the counting relays with the terminals of the arc served by brush 201, the functioning of which will be described hereinafter. Start 45 key 240 is now depressed to start the automatic progression of switch 200. The operation of key 240 establishes a circuit which may be traced from grounded battery, winding of relay 213, operated contact of key 240, right armature and back contact of relay 212, conductor 209, normal contact of the arc served by brush 204, to ground. Relay 213 is energized in this circuit. If the incoming selector switch shown in Fig. 3 50 is made busy due to the fact that it has been seized by another selector switch, relay 212 is operated to prevent the operation of relay 213. A circuit for the energization of relay 212 may be traced from ground on conductor 55 306, sleeves of jack 304 and plug 234, sleeve conductor of patching cord 233, sleeves of plug 232 and jack 231, conductor 207, brush 205 and its associated normal contact, conductor 261, right armature and back contact 60 of relay 217, conductor 262, winding of relay 65 212, to grounded battery. The energization of relay 212 establishes a circuit for lighting lamp 228 to indicate the busy condition, from grounded battery, resistance 223, lamp 228, right armature and front contact of relay 212, conductor 209, normal contact of the arc served by brush arm 204, to ground. The energizing circuit of relay 213 is opened at the right armature and back contact of relay 212 and this relay will not be actuated, 70 preventing the procedure of test of a selector switch that is busy. If, however, the incoming selector switch shown in Fig. 3 is idle, relay 213 is energized over the circuit 75 previously traced upon the operation of key 240. A locking circuit for relay 213, effective on the release of key 240, may be traced from grounded battery, through the winding of relay 213, left armature and front contact of relay 213, winding of relay 217, right armature and front contact of relay 213, left 80 armature and back contact of relay 211, conductor 255, armature and back contact of counting relay 11, to ground. Relay 217 is energized in this circuit, completing a circuit from grounded battery, winding, armature and back contact of magnet 200, brush arm 203 and its associated normal contact, conductor 263, left armature and front contact of relay 217, armature and back contact 85 of relay 220, to ground. Magnet 200 interrupts its own circuit, stepping the brush assembly of the associated switch to contact 2. 90

A circuit may now be traced from grounded battery, winding of relay 221, conductor 264, brush arm 204 and its associated strapped contacts, to ground. Relay 221 upon energizing, connects to the testing circuit through its armatures, conductors 242 and 266, leading from the incoming selector. 95 These conductors are normally open to prevent connecting a busy incoming selector switch to the test circuit. A circuit is also completed for lighting guard lamp 229, extending through resistance 224, lamp 229, conductor 265, to ground or brush 204. Magnet 200 is again energized from grounded battery, winding, armature and back contact of magnet 200, brush arm 203 and its associated contact 2, to ground. The switch is thus rotated to position 3. A circuit now 100 extends from grounded battery, winding of relay 10, conductor 121, normal contact of key 256, conductor 267, contact 3 of the arc served by brush 202, to ground. Relay 10 105 is energized in this circuit and connects grounded battery through its five right armatures and back contacts to the windings of counting relays 0 to 9. At its left armature and front contact, it extends grounded battery over conductor 122 through the winding of relay 220 to ground, energizing this relay. The energization of relay 220 causes 110 the energization of stepping magnet 200 through brush 203 and its associated contact 115 202, to ground. Magnet 200 is again energized from grounded battery, winding, armature and back contact of magnet 200, brush arm 203 and its associated contact 2, to ground. The switch is thus rotated to position 3. A circuit now 120 extends from grounded battery, winding of relay 10, conductor 121, normal contact of key 256, conductor 267, contact 3 of the arc served by brush 202, to ground. Relay 10 125 is energized in this circuit and connects grounded battery through its five right armatures and back contacts to the windings of counting relays 0 to 9. At its left armature and front contact, it extends grounded battery over conductor 122 through the winding of relay 220 to ground, energizing this relay. The energization of relay 220 causes 130 the energization of stepping magnet 200 through brush 203 and its associated contact 135 202, to ground.

tact 3, armature and front contact of relay 220 to ground, rotating the switch from position 3 to position 4.

With the switch brushes engaging the position 4 contacts, a fundamental circuit for incoming brush selection is established. This circuit may be traced from grounded battery, right winding of relay 311 in Fig. 3, upper contacts of sequence switch spring 321, resistance 315, upper contact of sequence switch spring 324, tips of jack 304 and plug 234, tip conductor of patching cord 233, tips of plug 232 and jack 231, conductor 242, left armature and front contact of relay 221, conductor 268, brush arm 206 and its associated contact 4, normal contact of key 256, conductor 251, left winding of relay 214, winding of relay 215, conductor 123, armature and back contact of the 0' counting relay, conductors 124 and 254, inner left armature and back contact of relay 212, conductor 235, normal contact of key 256, conductor 252, armature and front contact of relay 221, conductor 266, rings of jack 231 and plug 232, ring conductor of patching cord 233, rings of plug 234 and jack 304, lower contact of sequence switch spring 323, resistance 316, lower contact of sequence switch spring 325, to ground. Relays 311 and 215 are energized in this circuit but relay 214 is polarized in the opposite direction to the current flow and, therefore, does not energize at this time. Relay 311 in attracting its outer left armature, establishes a circuit from grounded battery, winding of the power magnet of sequence switch 300, lower contact of sequence switch spring 328, outer left armature and front contact of relay 311, lower contact of sequence switch spring 322, to ground, for rotating this sequence switch out of position 1 and into position 2. In position 2, a holding circuit for relay 311 may be traced from grounded battery, right winding of relay 311, right contacts of sequence switch spring 321, right armature and front contact of relay 311, left contacts of sequence switch spring 336, resistance 315, upper contact of sequence switch spring 324, tips of jack 304, and plug 234, tip conductor of patching cord 233, tips of plug 232 and jack 231, conductor 242, left armature and front contact of relay 221, conductor 268, brush 206 and its associated contact 4, normal contact of key 256, conductor 251, left winding of relay 214, winding of relay 215, conductor 123, armature and back contact of counting relay 0', conductors 124 and 254, inner left armature and back contact of relay 212, conductor 235, normal contact of key 256, conductor 252, right armature and front contact of relay 221, conductor 266, rings of jack 251 and plug 232, ring conductor of patching cord 233, rings of plug 234 and jack 304, lower contact of sequence switch spring 323, resistance

316, lower contact of sequence switch spring 335, to ground. With sequence switch 300 in position 2, a circuit is also established for energizing up-drive magnet 302. This circuit may be traced from 70 grounded battery, winding of up-drive magnet 302, upper right contact of sequence switch spring 334, outer left armature and front contact of relay 311, lower contact of sequence switch spring 322, to ground. The 75 selector switch elevator is now driven upward in the well known manner and in its upward movement brush 341 is intermittently brought into contact with the conducting portion of commutator segment 344. 80 Thus, a shunt circuit is established to cause the intermittent deenergization of stepping relay 215. This circuit may be traced from ground through the lower contact of sequence switch spring 333, brush 341, commutator 344, lower contacts of sequence switch spring 336, to a junction point in the circuit established for energizing relays 311 and 215. The shunt circuit will not cause the release 85 of relay 311, but will cause the release 90 of relay 215.

The initial energization of relay 215 over the fundamental circuit establishes a circuit for energizing counting relay 1 from ground, 95 armature and front contact of relay 215, conductor 253, brush 201 and its associated contact 4, conductor 125, left operated contact of key 133, armature and back contact of counting relay 1', winding of counting relay 1, conductor 175, outermost right armature and front contact of relay 10, to grounded battery. Counting relay 1, upon energizing, establishes a locking circuit for itself and an operating circuit for counting relay 1' through the winding of counting 100 relay 1' and its own armature and front contact to ground, which circuit becomes effective upon the first deenergization of stepping relay 215. The upward movement of the incoming selector switch elevator 105 causes the brush 341 to move from the conducting portion of commutator segment 344 to an insulated portion of this segment, which will remove the shunt from stepping relay 215 and cause its reenergization over 110 the same circuit as previously traced. The energization of relay 215 establishes a circuit from ground, armature and front contact of relay 215, conductor 253, brush 201 and its associated contact 4, conductor 125, left operated contact of key 133, armature and front contact of counting relay 1', winding of counting relay 0, outermost 115 right armature and front contact of relay 10, to grounded battery for energizing counting relay 0. The upward movement of the incoming selector switch elevator again establishes the shunt circuit, causing the release of relay 215. Upon the release 120 of relay 215, a circuit is established from 125

ground through the armature and contact of counting relay 0, windings of counting relays 0' and 11 in parallel, winding of counting relay 0 outermost right armature and front contact of relay 10, to grounded battery. Relays 0' and 11 are energized in this circuit.

The operation of counting relay 0' opens the fundamental circuit to cause the deenergization of relay 311, which is effected as soon as brush 341 is moved to an insulated portion of commutator segment 344 next above the conducting segment, which caused the second release of stepping relay 215. 15 Relay 311 upon deenergizing, opens at its outer left armature and front contact the energizing circuit for up-drive magnet 302, which deenergizes, causing the arrest of the upward movement of the incoming selector switch elevator. A circuit is also established from grounded battery, winding of the power magnet of sequence switch 300, upper left contact of sequence switch spring 328, inner left armature and back contact of relay 215, to ground for moving this sequence switch out of position 2 and into position 3.

Relay 11 at its armature and back contact opens the holding circuit for relays 213 and 217, which deenergize, and also establishes a circuit for actuating magnet 200. 30 This circuit extends from grounded battery, winding, armature and back contact of magnet 200, brush 203 and its associated contact 4, conductor 245, armature and front contact of relay 11, to ground. The switch is thus rotated from position 4 to position 5. When brush 202 leaves terminal 4, the circuit through relay 10 is opened, causing this relay to deenergize, which in turn causes the deenergization of the counting relays 40 and relay 220. The deenergization of relay 220 completes a circuit from grounded battery, winding, armature and back contact of magnet 200, brush 203 and its associated contact 5, armature and back contact of relay 220, to ground for rotating the switch from position 5 to position 6.

A circuit now extends from grounded battery, winding of relay 10, conductor 121, 50 normal contact of key 256, conductor 267, contact 6 of the arc served by brush 202, to ground for energizing relay 10. The energization of relay 10 re-establishes the circuit for energizing relay 220, which closes a circuit from grounded battery, winding, armature and back contact of magnet 200, brush 203 and its associated contact 6, armature and front contact of relay 220, to ground for rotating the switch from position 6 to 60 position 7. With the switch in position 7, the fundamental circuit is again established for incoming group selection.

This fundamental circuit is the same as previously traced, with the exception that 65 position 3 of sequence switch 300 and con-

tact 7 of the arc served by brush 206 are used instead of position 1 and contact 4, respectively. Relays 311 and 215 are energized in this circuit. A circuit is then established from grounded battery, winding 70 of the power magnet of sequence switch 300, lower contact of sequence switch spring 328, outer left armature and front contact of relay 311, lower contact of sequence switch spring 322, to ground for rotating this sequence switch out of position 3 into position 4. The holding circuit for relay 311 is again established in position 4 as previously traced. A circuit is also established from grounded battery, winding of trip magnet 80 303, right contacts of sequence switch spring 335, to ground. The energization of the trip magnet actuates the trip rod so that on subsequent upward movement of the incoming selector switch elevator, brushes 350, 351, and 352 will be brought into engagement with the bank terminals in the well known manner. A circuit is now established from grounded battery, winding of up-drive magnet 302, upper right contact of 85 sequence switch spring 334, outer left armature and front contact of relay 311, to ground at the lower contact of sequence switch spring 322. The incoming selector switch elevator and commutator brushes are now driven in an upward movement causing brush 342 to engage the conducting portion of commutator 345 in order to establish a shunt circuit for deenergizing stepping relay 215. This shunt path may be traced from ground at the lower contact of sequence switch spring 333, brush 342, conducting portion of commutator 345, upper right and lower left contacts of sequence switch spring 336, to a point of junction in 90 the fundamental circuit where an effective shunt is placed around relay 215.

The initial energization of relay 215 upon the establishment of the fundamental circuit, completes a circuit for energizing counting relay 2. This circuit may be traced from ground through the armature and front contact of relay 215, conductor 253, brush 201 and its associated contact 7, conductor 269, right operated contact of key 133, left operated contact of key 141, armature and back contact of counting relay 2', winding of counting relay 2, conductor 176, fourth outer armature and front contact of relay 10, to grounded battery. The energization of counting relay 2 establishes a holding circuit for itself and an energizing circuit for counting relay 2' which is effective upon the release of relay 215 which deenergizes when relay 342 engages the conducting portion of commutator 345. 100

As the incoming selector switch elevator 115 is driven in an upward movement, brush 342 intermittently engages with non-conducting 120

and conducting portions of commutator segment 345, thus causing the intermittent energization and deenergization of relay 215. Counting relays 1, 1', 0, 0', and 11 are thus operated in the well known manner.

The energization of counting relay 0' opens the fundamental circuit, causing the deenergization of relay 311 when brush 342 reaches the next non-conducting portion of 10 commutator segment 345 causing the release of relay 215 and the energization of counting relay 0'. The deenergization of relay 311 arrests the upward movement of the incoming selector switch elevator and causes 15 the energization of sequence switch magnet 300 in a circuit which may be traced from grounded battery through the winding of the magnet, upper left contact of sequence switch spring 328, inner left armature and 20 back contact of relay 311, to ground. Sequence switch 300 is thus rotated out of position 4 into position 5.

A circuit is now established from grounded battery, left winding of relay 311, right 25 contacts of sequence switch spring 327, to ground for energizing relay 311, which in turn completes a circuit from grounded battery, winding of the power magnet of sequence switch 300, lower contact of sequence switch spring 328, outer left armature and front contact of relay 311, to ground at the lower contact of sequence switch spring 322 for rotating this sequence switch out of position 5 and into position 6. In position 6, 30 the incoming selector switch is operated to hunt for an idle trunk leading to a final selector circuit. Since the trunk hunting feature of this incoming selector switch is described in detail in the previously mentioned Patent No. 1,395,977, it will not be described here, but it will be assumed that an idle final selector switch has been found, causing the deenergization of relay 311.

The deenergization of relay 311 completes 45 a circuit from ground at the upper right contact of sequence switch spring 329, right armature and back contact of relay 311, right contacts of sequence switch spring 330, brush 350 to terminal 353, for rendering this 50 final selector busy to other hunting incoming selectors. The deenergization of relay 311 also completes a circuit from grounded battery, winding of the power magnet of sequence switch 300, upper left contact of sequence switch spring 328, inner left armature and back contact of relay 311, to ground for rotating the sequence switch out of position 6 and into position 7.

In position 7 of sequence switch 300, a 60 circuit is established for operating relay 311. This relay may be traced from grounded battery, through the left winding of relay 311, right contacts of sequence switch spring 327, to ground. Relay 311, upon energizing, 65 closes a circuit from grounded battery, wind-

ing of the power magnet of sequence switch 300, lower contact of sequence switch spring 328, outer left armature and front contact of relay 311, to ground through the lower contact of sequence switch spring 322 for 70 rotating this sequence switch out of position 7 and into position 8, in which it will remain until the final selector switch has completed its units selection. In position 8, a holding circuit for relay 311 may be 75 traced from grounded battery through the right winding of relay 311, right contacts of sequence switch spring 321, right armature and front contact of relay 311, lower right contact of sequence switch spring 331, brush 80 351, terminal 354, upper left and lower right contacts of sequence switch spring 421, resistance 450, lower left contact of sequence switch spring 419, to ground.

The energization of relay 11, upon the 85 completion of incoming selector switch group selection as explained above, closes a circuit from grounded battery, winding, armature and back contact of magnet 200, brush 203 and its associated seventh contact, 90 conductor 245, armature and front contact of relay 11, to ground for rotating this switch from position 7 to position 8. When brush 202 leaves its seventh contact, the energizing circuit for relay 10 is opened. The 95 operated counting relays and relay 220 are then deenergized. A circuit for switch magnet 200 may now be traced from ground through the armature and back contact of relay 220, brush 203 and its associated contact 100 8, armature, back contact and winding of magnet 200, to grounded battery for rotating this switch from position 8 to position 9. In this position, a circuit is again established for relay 10 over conductors 121 and 248, contact 9 of the arc served by brush 202, to ground. Relay 220 energizes as before and magnet 200 rotates the switch from position 9 to position 10 in a circuit which may be traced from grounded battery, winding, armature and back contact of magnet 200, brush 203 and its associated contact 9, armature and front contact of relay 220, to ground. 105

The fundamental circuit is now extended 110 to the final selector switch as shown in Fig. 4. This circuit may be traced from grounded battery, left contact of sequence switch spring 416, right winding of relay 407, lower left contact of sequence switch springs 115 418 and 422, terminal 355, brush 352, upper left contact of sequence switch spring 332, resistance 315, upper right contact of sequence switch spring 324, tips of jack 304 and plug 284, tip conductor of patching 120 cord 233, tips of plug 232 and jack 231, conductor 242, left armature and front contact of relay 221, conductor 268, brush 206 and its associated contact 10, conductor 251, left 125 winding of relay 214, winding of relay 215, 120

conductor 123, armature and back contact of 0' counting relay, conductors 124 and 254, inner left armature and back contact of relay 212, conductor 235, normal contact of key 256, conductor 252, right armature and front contact of relay 221, conductor 266, rings of jack 231 and plug 232, ring conductor of patching cord 233, rings of plug 234 and jack 304, lower right contact of sequence switch spring 323, resistance 316, lower contact of sequence switch spring 335, to ground. Relays 407 and 215 are energized in this circuit.

The energization of relay 407 establishes a circuit for energizing relay 406 which may be traced from grounded battery, left winding of relay 406, upper left contact of sequence switch spring 417, conductor 408, left armature and front contact of relay 407, upper contact of sequence switch spring 410, to ground. Upon energizing, relay 406 completes a locking circuit for itself through the armature and back contact of relay 405, left armature and front contact of relay 406, terminal 353 and brush 350, lower right and upper left contacts of sequence switch spring 330, to ground. A circuit is also completed at this time from grounded battery, winding of the power magnet of sequence switch 400, lower contacts of sequence switch spring 411, right armature and front contact of relay 406, to ground for rotating this sequence switch out of position 1 and into position 2. Relay 407 is held energized in a circuit which may be traced from grounded battery, left contact of sequence switch spring 416, right winding of relay 407, lower contact of sequence switch spring 415, right armature and front contact of relay 407, lower right contact of sequence switch spring 418, lower left contact of sequence switch spring 422, and thence over the fundamental circuit to ground as previously traced.

In position 2 of sequence switch 400, a circuit is established from grounded battery, winding of up-drive magnet 403, upper right contact of sequence switch spring 426, conductor 408, left armature and front contact of relay 407, to ground at the upper left contact of sequence switch spring 410. The final selector switch elevator is now driven upward to make brush selection and brush 431 is brought into contact with commutator segment 434, thus intermittently establishing a shunt for relay 215. This shunt circuit extends from ground through the upper left contact of sequence switch spring 419, brush 431, commutator segment 434, upper right contact of sequence switch spring 422, to the fundamental circuit.

The initial operation of relay 215 over the fundamental circuit establishes an energizing circuit for counting relay 1. This circuit may be traced from ground, armature

and front contact of relay 215, conductor 253, brush 201 and its associated contact 10, conductor 244, operated contact of key 141, conductor 111, armature and back contact of counting relay 11, winding of counting relay 1, outermost armature and front contact of relay 10, to grounded battery. Counting relay 1, upon energizing, establishes a locking circuit for itself and an operating circuit for relay 1' which is effective upon the first release of stepping relay 215 when the shunt is established. Counting relays 0, 0' and 11 will be operated thereafter in the well known manner. Relay 0' on energizing, opens the fundamental circuit, causing the deenergization of relay 407 when brush 431 moves upward to a non-conducting segment of commutator 434.

Relay 407 opens the energizing circuit for up-drive magnet 302 which upon deenergizing arrests the upward motion of the selector switch elevator. A circuit is completed from grounded battery, winding of the power magnet of sequence switch 400, upper right contact of sequence switch spring 413, left armature and back contact of relay 407, upper left contact of sequence switch spring 410, to ground for rotating this sequence switch out of position 2 and into position 3.

Relay 11, upon energizing, closes a circuit from grounded battery, winding, armature and back contact of switch magnet 200, brush 203 and its associated contact 10, conductor 247, outer left armature and back contact of relay 216, conductor 245, armature and front contact of relay 11, to ground for rotating the switch from position 10 to position 11. When brush 202 leaves contact 10, the energizing circuit for relay 10 is broken, causing this relay to deenergize. As a result, the counting relays and relay 220 are also deenergized. The release of relay 220 completes a circuit for energizing magnet 200 through brush 203 and its associated contact 11, armature and back contact of relay 220, to ground. The switch is thus rotated from position 11 to position 12.

With brush 202 engaging contact 12, an actuating circuit for relay 10 is again closed. Relay 10 energizes, in turn energizing relay 220. Magnet 200 is actuated to advance the switch from position 12 to position 13 in a circuit which extends from grounded battery, winding of magnet 200, brush 203 and its associated contact 12, armature and front contact of relay 220, to ground. With the switch standing in position 12, the fundamental circuit is again established for controlling tens selection at the final selector switch.

With sequence switch 400 in position 3, the fundamental circuit is established for energizing relays 407 and 215. This circuit extends from grounded battery, left contact of sequence switch spring 416, right winding

of relay 407, lower left contacts of sequence switch springs 418 and 422, and thence over the fundamental circuit as previously traced through the winding of relay 215 to ground 5 at sequence switch spring 335. Upon the actuation of relay 407, a circuit is established from grounded battery, winding of the power magnet of sequence switch 400, lower contact of sequence switch spring 413, 10 conductor 408, left armature and front contact of relay 407, to ground at the upper contact of sequence switch spring 410 for rotating this sequence switch out of position 3 and into position 4. The holding circuit 15 for relay 407 as previously traced, is again established.

In positions 3 to 5, an obvious circuit is established for energizing trip magnet 404 to cause the actuation of the trip rod in the 20 well known manner. Brushes 437, 438 and 439 are now prepared to engage the bank terminals upon the subsequent upward movement of the selector switch elevator.

In position 4, a circuit is established from 25 grounded battery, winding of the high speed up-drive magnet 403, upper right contact of sequence switch spring 426, conductor 408, left armature and front contact of relay 407, to ground at the upper left contact of sequence switch spring 410. The selector switch elevator is thus driven in an upward movement to bring brush 432 into engagement with commutator segment 435. The 30 engagement of this brush with the conducting portion of commutator segment 435 establishes a shunt circuit for releasing stepping relay 215. This circuit may be traced from ground, through the upper left contact of sequence switch spring 419, brush 432, 35 conducting portion of commutator segment 435, upper right contact of sequence switch spring 418, lower left contact of sequence switch spring 422, thence over the fundamental circuit causing relay 215 to deener- 40 gize.

The initial energization of stepping relay 215 completes a circuit extending from ground, armature and front contact of relay 215, conductor 253, brush 201 and its associated contact 13, conductor 126, operated contact of key 159, conductor 174, armature and back contact of counting relay 9', winding of counting relay 9', innermost right armature and front contact of relay 10, to 45 grounded battery. Counting relay 9' energizes in this circuit and establishes a holding circuit for itself and an operating circuit for counting relay 9' which is effective upon the first release of stepping relay 215. Upon 50 the upward movement of the final selector switch elevator, brush 432 is intermittently engaged with the conducting and non-conducting portions of commutator segment 435, causing the alternate operation and release of relay 215. The counting relays are

energized due to the deenergization of relay 215 in the well known manner until all of the counting relays, including relay 11, have been energized.

The energization of counting relay 0' 70 opens the fundamental circuit, causing the deenergization of relay 407 as soon as the shunt ground is removed at commutator 435. Relay 407 on deenergizing, arrests the upward movement of the final selector switch 75 elevator and establishes a circuit for rotating the sequence switch 400 out of position 4 and into position 5, which may be traced from grounded battery, winding of the power magnet of sequence switch 400, upper 80 right contact of sequence switch spring 418, left armature and back contact of relay 407, to ground at the upper left contact of sequence switch spring 410.

The energization of relay 11 closes a circuit from grounded battery, winding, armature and back contact of magnet 200, brush 203 and its associated contact 13, conductor 245, armature and front contact of relay 11, to ground. The switch is thus rotated from 90 position 13 to position 14, and the energizing circuit of relay 10 is opened. As a result, the counting relays and relay 220 deenergize. A circuit is then established from 95 grounded battery, winding, armature and back contact of magnet 200, brush 203 and its associated contact 14, armature and back contact of relay 220, to ground for rotating this switch from position 14 to position 15. In this position, the energizing circuit for 100 relay 10 is again established, in turn completing an obvious circuit for relay 220. A circuit may then be traced from grounded battery, winding, armature and back contact of magnet 200, brush 203 and its associated contact 15, armature and front contact of relay 220 for moving the switch from position 15 to position 16. With the switch in 105 position 16, the fundamental circuit for final units selection is reestablished.

With sequence switch 400 in position 5, a circuit is established from grounded battery, left contact of sequence switch spring 416, right winding of relay 407, lower left contacts of sequence switch springs 418 and 422, and thence over the fundamental circuit through the winding of relay 215, to ground at the contact of sequence switch 115 spring 235 as previously traced. The energization of relay 407 closes a circuit from grounded battery, winding of the power magnet of sequence switch 400, lower contact of sequence switch spring 413, left armature and front contact of relay 407, upper contact of sequence switch spring 410, to ground for rotating this sequence switch 120 out of position 5 and into position 6, in which a holding circuit for relay 407 is again established as previously traced. The final units selection may now be made. 125

With sequence switch 400 in position 6, a circuit is established for the slow speed up-drive magnet 402. This circuit may be traced from grounded battery, winding of magnet 402, lower contact of sequence switch spring 417, conductor 408, left armature and front contact of relay 407, to ground at the upper contact of sequence switch spring 410. The final selector switch elevator is now actuated, causing the upward movement of brush 431 over commutator segment 434. Since the final selector switch is to be directed to the first or 0 terminals in a group of ten, the shunt circuit for deenergizing relay 215 is immediately established. This circuit may be traced from ground through the upper left contact of sequence switch spring 422, to a junction point in the fundamental circuit effective for maintaining relay 407 energized and releasing relay 215.

The initial operation of relay 215 establishes a circuit from ground, armature and front contact of relay 215, conductor 253, brush 201 and its associated contact 16, conductor 127, operated contact of key 160, conductor 110, winding of counting relay 0, conductor 175, outermost right armature and front contact of relay 10, to grounded battery. Counting relay 0 energizes in this circuit and completes a holding circuit for itself and an operating circuit for counting relays 0' and 11 which is effective upon the release of relay 215.

Relay 0', upon energizing, opens the fundamental circuit, permitting the deenergization of relay 407 as soon as brush 431 reaches a non-conducting portion of commutator segment 434. The upward movement of the selector switch elevator is then arrested and a circuit is completed from grounded battery, winding of the power magnet of sequence switch 400, upper right contact of sequence switch spring 413, left armature and back contact of relay 407, upper left contact of sequence switch spring 410 to ground. Sequence switch 400 is rotated out of position 6 and into position 9 under the control of sequence switch spring 409.

The energization of relay 11 completes a circuit from ground through the armature and front contact of relay 11, conductor 245, contact 16 of the arc served by the brush 203, armature, back contact and winding of switch magnet 200, to grounded battery. The switch is thus rotated from position 16 to position 17 opening the energizing circuit for relay 10. The deenergization of relay 10 causes the deenergization of the counting relays and relay 220. A circuit now extends from grounded battery, winding, armature and back contact of switch magnet 200, brush 203 and its associated contact 17, armature and front contact of relay 220 to ground, for rotating the switch from position 17 to position 18. With brush 206 in

contact with contact 18 of its associated arc it again establishes the fundamental circuit, previously traced. The switch now remains in position 18 to further control the incoming selector switch of Fig. 3 as will be described later.

It will be remembered that relay 407 upon deenergizing caused sequence switch 400 to be rotated to position 9. In position 9 a circuit may be traced from grounded battery, left contact of sequence switch spring 416, right winding of relay 407, lower right and upper left contacts of sequence switch spring 415 to ground through the right armature and front contact of relay 406. Relay 407 is energized in this circuit and establishes a circuit from grounded battery, winding of the power magnet of sequence switch 400, lower contact of sequence switch spring 413, left armature and front contact of relay 407, upper contact of sequence switch spring 410 to ground for rotating the sequence switch out of position 9 and into position 12 under the control of the sequence switch magnet contact 409.

As sequence switch 400 leaves position 8½ the holding circuit for relay 311 is opened and this relay deenergizes. This holding circuit, it will be remembered, extended from grounded battery, right winding of relay 311, right contacts of sequence switch spring 321, right armature and front contact of relay 311, lower right contact of sequence switch spring 331, brush 351, terminal 354, upper left and lower right contacts of sequence switch spring 421, resistance 450 to ground through the lower left contact of sequence switch spring 419. The deenergization of relay 311 completes a circuit from grounded battery, winding of the power magnet of sequence switch 300, upper left contact of sequence switch spring 328, inner left armature and back contact of relay 311 to ground, for moving this sequence switch out of position 8 and into position 9.

In position 9 of the incoming selector sequence switch, battery and ground are reversed with relation to the fundamental circuit. This is done to signal the controlling circuit in Fig. 2 when final selections have been completed and relay 311 released. This circuit extends from grounded battery through the right winding of relay 311, lower contacts of sequence switch spring 325, resistance 316, lower right contact of sequence switch spring 323, rings of jack 304 and plug 234, ring conductor of patching cord 233, rings of plug 232 and jack 231, conductor 266, right armature and front contact of relay 221, conductor 252, normal contact of key 256, conductor 235, inner left armature and back contact of relay 212, conductors 254 and 124, armature and back contact of counting relay 0', conductor 123, winding of relay 215, left winding

of relay 214, conductor 251, contact 18 of the arc served by brush 206, conductor 268, left armature and front contact of relay 221, conductor 242, tips of jack 231 and plug 232, tip conductor of patching cord 233, tips of plug 234 and of jack 204, upper contact of sequence switch spring 324, resistance 315, left contacts of sequence switch spring 336, to ground at the upper contacts of sequence switch spring 330. Relays 311, 215 and 214 are energized in this circuit.

The energization of relay 214 establishes an actuating path for relay 216 and a locking circuit for itself which may be traced from ground through brush 204 and its associated contact, conductors 269 and 265, armature and front contact of relay 214 through the windings of relays 214 and 216 in parallel to grounded battery. Relay 216 establishes a circuit from grounded battery, resistance 225, lamp 230, outer right armature and front contact of relay 216, normal contact of key 256, conductor 267, contact 18 of the arc served by brush 202 to ground for lighting lamp 230 as an indication to the test man of the progress of the test. A circuit is also completed from ground, armature and front contact of relay 215, conductor 253, brush 201 and its associated contact 18, inner left armature and front contact of relay 216, conductors 180 and 110, winding of counting relay 0, conductor 175, outermost right armature and front contact of relay 10 to grounded battery for energizing counting relay 0. It should be noted that relay 10 was energized over conductor 121 to ground at brush 202 as traced for lamp 230. The energization of counting relay 0 establishes a locking circuit for itself and an operating circuit for counting relays 0' and 11. Relay 215 while energized, maintains a shunt circuit around the windings of counting relays 0' and 11 until upon further advance of sequence switch 300 as will be presently described, relay 215 is deenergized.

Returning to Fig. 3, a circuit is established upon the energization of relay 311 from grounded battery, winding of relay 310, upper right contact of sequence switch spring 326, right armature and front contact of relay 311, upper contacts of sequence switch spring 330 to ground. Relay 310 is energized in this circuit and completes a circuit from grounded battery, winding of the power magnet of sequence switch 300, armature and front contact of relay 310, left contacts of sequence switch spring 330 to ground for rotating this sequence switch out of position 9 into position 10. As sequence switch 300 leaves position 9, the fundamental circuit traced through relays 311, 214 and 215 is opened, deenergizing relay 215. Counting relays 0' and 11 are then energized from grounded battery, out-

ermost right armature and front contact of relay 10, winding of counting relay 0, windings of counting relays 11 and 0' in parallel, armature and front contact of counting relay 0 to ground. The energization of counting relay 0' causes the fundamental circuit to remain open until the control circuit of Figs. 1 and 2 is in position to further control the incoming selector of Fig. 3. The energization of counting relay 11 establishes a circuit for energizing magnet 200 from ground through the armature and front contact of counting relay 11, conductor 245, contact 18 of the arc served by brush 203, armature, back contact and winding of magnet 200 to grounded battery, rotating this switch from position 18 to position 19 which causes the release of relays 10, 220 and the counting relays as previously described.

With brush 206 on contact 19 what is known as a trunk closure condition with relation to the incoming selector switch of Fig. 3 is established. This simulates the connection of the incoming selector switch to the calling subscriber preceding the ringing of the wanted subscriber's station. The circuit established for trunk closure may be traced from grounded battery, through the right winding of relay 311, upper contacts of sequence switch spring 321, resistance 315, upper contact of sequence switch spring 324, tip of jack 304 and of plug 234, tip conductor of patching cord 233, tip of plug 232 and of jack 231, conductor 242, left armature and front contact of relay 221, conductor 268, brush 206 and its associated contact 19, conductor 259, right armature and back contact of relay 246, resistance 226, winding of polarized relay 218, inner left armature and back contact of relay 212, conductor 235, normal contact of key 256, conductor 252, right armature and front contact of relay 221, conductor 266, ring of jack 231 and of plug 232, ring conductor of patching cord 233, ring of plug 234 and of jack 304, lower contact of sequence switch spring 323, resistance 316 to ground through the lower contact of sequence switch spring 335. Since relay 218 is polarized in the opposite direction to the current flowing through this circuit, it will not energize. Relay 311, however, energizes and completes a circuit from grounded battery, winding of relay 310, upper right contact of sequence switch spring 326, right armature and front contact of relay 311 to ground through the upper contacts of sequence switch spring 330. Relay 310 is energized and completes a circuit from grounded battery, winding of the power magnet of sequence switch 300, armature and front contact of relay 310, left contacts of sequence switch spring 330 to ground for rotating this sequence switch out of position 10 and into position 11.

With sequence switch 300 in position 11,

a holding circuit for relay 311 may be traced from grounded battery through its left winding, armature and back contact of relay 314, upper left contact of sequence switch spring 334, outer left armature and front contact of relay 311, upper contact of sequence switch spring 332, sleeve of jack 304 and of plug 234, sleeve conductor of patching cord 233, sleeve of plug 232 and of jack 10 231, conductor 207, brush 205 and its associated contact 19, winding of relay 219, resistance 257, contact 19 of the arc served by brush 204 to ground.

Resistance 257 is of low value and resistance 258 is high. A potentiometer is thus formed so that relay 219 will be energized from either grounded battery or ground on the sleeve of jack 304 and remains in that condition as the control switch advances during the remainder of the test on the incoming selector switch. The energization of relay 219 completes an obvious circuit for energizing relay 210. Relay 210 establishes a circuit from grounded battery, resistance 222, outer right armature and front contact of relay 210, left armature and back contact of relay 236, lamp 227, armature and back contact of relay 218, left armature and front contact of relay 210 to ground, for lighting this lamp. The utility of this lamp will be fully described later. A circuit is also completed from grounded battery, winding, armature and back contact of magnet 200, brush 203 and its associated contact 19, left armature and front contact of relay 210 to ground for rotating this switch to position 20.

The switch is then advanced to position 21 because of the presence of ground on terminal 20 of the arc served by brush 203 through the contact of key 208.

Sequence switch 300 does not remain in position 11 but is advanced to position 13 by means of the action of interrupter 307. Relay 310 is energized in position 11 from grounded battery, winding of relay 310, upper left contact of sequence switch spring 326, upper contact of interrupter 307 to ground. The energization of relay 310 completes a circuit from grounded battery, winding of the power magnet of sequence switch 300, armature and front contact of relay 310, left contacts of sequence switch spring 330 to ground for advancing this sequence switch out of position 11 and into position 12. As sequence switch 300 leaves position 11, relay 310 is deenergized. Upon the closure of the lower contact of interrupter 307, relay 310 is again energized in an obvious manner. Sequence switch 300 is then advanced to position 13 over the same path which advances it into position 12.

Returning now to Fig. 4, it will be remembered that sequence switch 400 rotated from position 9 to position 12 upon the energiza-

tion of relay 407. As this sequence switch enters position 11 a circuit may be traced from grounded battery, resistance 449, sleeves of plug 444 and of jack 445, terminal 440, brush 437, right contacts of sequence switch spring 420, right armature and front contact of relay 407, upper right contact of sequence switch spring 415, right winding of relay 407, lower left contact of sequence switch spring 418, upper left contact of sequence switch spring 422, winding of relay 405 to ground. Relay 407 is held energized and relay 405 is energized in this circuit and the latter opens at its armature and back contact the holding circuit for relay 406 75 which thereupon deenergizes. The deenergization of relay 406 causes sequence switch 400 to advance, upon arriving in position 12, out of this position and into position 13 over a circuit which may be traced from grounded battery, winding of the power magnet of sequence switch 400, lower right and upper left contacts of sequence switch spring 411 to ground through the right armature and back contact of relay 406. With sequence switch 400 in position 13, relay 405 deenergizes and relay 406 is reenergized over a circuit from grounded battery, left winding of relay 406, upper right contact of sequence switch spring 419 to ground. Relay 406, upon energizing, locks through its left armature and front contact to ground at the contacts of sequence switch spring 330. A circuit is now completed from grounded battery, winding of the power magnet of sequence switch 400, lower contacts of sequence switch spring 411, right armature and front contact of relay 406 to ground for advancing this sequence switch out of position 13 and into position 14. Relay 407 remains locked over the lower right contact of sequence switch spring 414, the left armature and front contact of relay 407 to ground at the upper contact of spring 410 after sequence switch 400 leaves position 12½. As sequence switch 400 enters position 14, with relay 407 operated a circuit may be traced from grounded battery, winding of down-drive magnet 401, lower right contact of sequence switch spring 426, conductor 408, left armature and front contact of relay 407 to ground at the upper contact of sequence switch spring 410. The final selector switch elevator is caused to move in a downward direction under the control of magnet 401. When brush 432 engages commutator segment 436, a circuit may be traced from grounded battery, winding of the power magnet of sequence switch 400, upper left contact of sequence switch spring 413, commutator segment 436, brush 432, upper left contact of sequence switch spring 419 to ground, for rotating this sequence switch out of position 14 and into position 17. As this sequence switch leaves position 14, the 100 105 110 115 120 125 130

taet of switch magnet 200, outer right armature front contact of relay 211 to ground through the contacts of the arc served by brush 204. Switch 200 is thus rotated from position 21 to position 22 and a circuit is then established for actuating switch magnet 200 from grounded battery through its winding, armature and back contact to ground through brush 203 and its associated contact 22. The switch is thus returned to its normal position. 75

Switch 200 in rotating to its normal position, opens all circuit paths to cause the de-energization of all operated relays in the control circuit of Fig. 2. When lamp 227 as a result of the return of the circuit of Fig. 2 to normal, is extinguished, plug 232 is removed from jack 231, plug 234 is removed from jack 304 and plug 444 is removed from jack 445 by the test man. Relay 311, which was held energized over the sleeve circuit extending to a ground in Fig. 2 is deenergized upon the restoration of switch 200. A circuit is then established from grounded battery, winding of the power magnet of sequence switch 300, upper left contact of sequence switch spring 328 to ground at the inner left armature and back contact of relay 311 for rotating this sequence switch from position 13 to position 18. In position 18 a circuit is established for downdrive magnet 301 from grounded battery through the winding of magnet 301 to ground at the right contacts of sequence switch spring 333. The incoming selector switch elevator is caused to move in a downward direction. When brush 342 engages commutator segment 346, a circuit is established from grounded battery, winding of the power magnet of sequence switch 300, upper right contact of sequence switch spring 328, commutator segment 346, brush 342, lower right contact of sequence switch spring 333 to ground for rotating this sequence switch out of position 18 and into its normal position 1. 110

When sequence switch 300 left position 16 $\frac{1}{4}$, ground on sleeve brush 350 was removed, causing the deenergization of relay 406 which had been held in an operated position over the sleeve conductor extending to ground at sequence switch spring 330. Upon the deenergization of relay 406 a circuit may be traced from grounded battery through the winding of the power magnet of sequence switch 400, lower right and upper left contacts of sequence switch spring 411 to ground at the right armature and back contact of relay 406, rotating the sequence switch into position 18. Since the final selector switch elevator has previously been restored a circuit is now established from grounded battery through the winding of the power magnet of sequence switch 400, upper left contact of sequence switch spring 413, commutator segment 436, brush 115 120 125 130

432, upper left contact of sequence switch spring 419 to ground for rotating this sequence switch out of position 18 and into its normal position 1.

5 This completes the description of a successful test of brush continuity on the incoming selector. A busy back flash is the indication that the call has gone through correctly since the necessary circuits cannot be 10 completed unless all the brushes are in contact with their respective terminals.

Brush continuity test of final selector.

A brush continuity test may also be made 15 on a final selector circuit, as shown in Fig. 4. To make this test, plug 232 is inserted in jack 231 and plug 234 is inserted in jack 453. The selector switch elevator of Fig. 4 is directed to any subscriber's line such as 20 that shown in Fig. 5 and terminating in terminals 427, 428 and 429. In Fig. 1 keys 139, 141, 159 and 168 are depressed to direct the final selector to the line shown in Fig. 5, for example, as are also start key 240 and 25 final key 256. The operation of key 240 establishes a circuit from grounded battery through the winding of relay 213, operated contact of key 240, right armature and back contact of relay 212, conductor 209, normal contact of the arc served by brush 204 to ground. Relay 213 is energized in this circuit. If the final selector switch shown in 30 Fig. 4 is found busy, relay 212 will be energized to ground on conductor 454 and lamp 228 will be lighted to indicate the busy condition. If relay 212 is not operated, relay 35 213 is energized and locked as before described and relay 217 is energized. Magnet 200 is then actuated to step the brush assembly of its associated switch to position 2.

Relay 221 is energized over the circuit 40 previously traced and connects the testing circuit through its armatures to conductors 242 and 266, leading to the final selector. Guard lamp 229 is lighted and switch 200 is rotated to position 3. A circuit now 45 extends from grounded battery, winding, armature and back contact of magnet 200, operated contact of key 256, conductor 267, contact 3 of the arc served by brush 202 to ground. The switch is thus rotated from 50 position 3 to position 5 since contacts 3 and 4 of the arc served by brush 202 are strapped together. The positions for making incoming brush selection are thus passed over and 55 this selection is not made. In position 5, magnet 200 is again energized over a circuit extending through its winding, armature and back contact, brush 203 and its associated contact 5 to ground at the armature and back contact of relay 220, rotating the 60 switch to position 6. With the brush assembly of this switch in positions 6 and 7, ground at brush 202 is again supplied

through the operated contact of key 256 to 65 magnet 200. The switch is thus rotated from position 6 to position 7 and then to position 8, since contact 7 is strapped to contact 6 in the arc of brush 202. Ground at the armature and back contact of relay 70 220 causes the switch to rotate to position 9. With the brush assembly resting in position 9, a circuit is established from grounded battery, winding of relay 10, conductor 121, contact 9 of the arc served by brush 202 to 75 ground. Relay 10 energizes, closing an obvious circuit for the energization of relay 220, which causes magnet 200 to rotate the switch to position 10 over a circuit which may be traced from grounded battery, winding, armature and back contact of magnet 200, brush 203 and its associated contact 9, armature and front contact of relay 220 to ground.

The fundamental circuit for controlling 85 final selections may now be traced from grounded battery, left contact of sequence switch spring 416, right winding of relay 407, lower left contacts of sequence switch springs 418 and 422, tips of jack 453 and plug 234, tip conductor of patching cord 233, tips of plug 232 and jack 231, conductor 242, left armature and front contact of relay 221, conductor 268, brush 206 and its associated contact 10, conductor 251, left winding of relay 214, winding of relay 215, conductor 123, armature and back contact of 0' counting relay, conductors 124 and 254, inner left armature and back contact of relay 212, conductor 235, operated contact of 100 key 256 to ground. Relays 407 and 215 are energized in this circuit.

Relay 407 then causes the energization of 105 relay 406 and sequence switch 400 is advanced into position 2 in a manner previously described. Final brush and tens selections are now made and the operation 110 proceeds in the same manner as described for the previous test with the switch controlled by magnet 200 in positions 10 and 111 13 and sequence switch 400 in positions 2 and 4. The fundamental circuit is then established for making units selection through the advance of the control switch to position 11 and the advance of sequence switch 400 115 to position 6. Slow speed updrive magnet 402 is then energized in the manner hereinbefore described for advancing the final selector switch elevator upwardly moving brush 431 over commutator segment 434. 120 Every time brush 431 engages a conducting portion of commutator 434, a shunt circuit for deenergizing stepping relay 215 is established. This shunt path may be traced from ground through the upper left contact 125 of sequence switch spring 419, brush 431, conducting portion of commutator segment 434, upper right and lower left contacts of

sequence switch spring 422, thence over the fundamental circuit, causing relay 215 to deenergize.

The initial energization of relay 215, upon the establishment of the fundamental circuit, completes a circuit for energizing counting relay 8. This circuit may be traced from ground through the armature and front contact of relay 215, conductor 253, brush 201 and its associated contact 16, conductor 127, operated contact of key 168, conductor 173, armature and back contact of counting relay 8', winding of counting relay 8, conductor 179, innermost right armature and front contact of relay 10 to grounded battery. Counting relay 8 energizes in this circuit and establishes a holding circuit for itself and an operating circuit for counting relay 8' which is effective upon the first release of stepping relay 215. On the upward movement of the final selector switch elevator, brush 431 is intermittently engaged with the conducting and non-conducting portions of commutator segment 434 causing the alternate operation and release of relay 215. The counting relays are energized due to the operation of relay 215 in the well known manner until all of the counting relays, including relay 11, have been energized. Relay 0' upon energizing, opens the fundamental circuit, causing the deenergization of relay 407 as soon as brush 431 reaches a non-conducting portion of commutator segment 434. The upward movement of the selector switch elevator is now arrested and brushes 437, 438 and 439 are in engagement with terminals 427, 428, and 429, respectively, leading to an idle line, as shown in Fig. 5. A circuit is completed from grounded battery, winding of the power magnet of the sequence switch 400, upper right contact of sequence switch spring 413, left armature and back contact of relay 407, upper left contact of sequence switch spring 410 to ground for rotating this sequence switch out of position 6 and into position 9 under the control of sequence switch spring 409.

The switch controlled by magnet 200 is then rotated from position 16 to position 18 in the manner previously described. A circuit may now be traced from grounded battery, winding, armature and back contact of magnet 200, operated contact of key 256, conductor 267, contact 18 of the arc served by brush 202 to ground. Magnet 200 is energized in this circuit and the brush assembly of the associated switch is rotated to position 19. As brush 205 moves from contact 18 to contact 19 the holding circuit for relay 406 which extends through its left winding, armature and back contact of relay 405, left armature and front contact of relay 406, conductor 454, sleeve of jack 453 and of plug 234, sleeve conductor of patching

cord 233, sleeve of plug 232 and of jack 231, conductor 207 to ground through brush 205 and its associated first 18 contacts is transferred through contact 19 of the arc served by brush 205, through the winding of relay 219, resistance 257, contact 19 of the arc served by brush 204, to ground. Relay 219 is then energized.

In position 9 of sequence switch 400, a circuit may be traced from grounded battery, left contact of sequence switch spring 416, right winding of relay 407, lower right and upper left contacts of sequence switch spring 415 to ground through the right armature and front contact of relay 406 which, so it will be remembered, is locked to ground on sleeve conductor 454. Relay 407 is energized and establishes a circuit for actuating sequence switch 400, rotating it out of position 9 and into position 12 under the control of sequence switch magnet contact 409. If the circuit to which the final selector is connected is idle the circuit through relay 405 and the right winding of relay 407 will be opened and the latter will deenergize. Since relay 406 is held energized a circuit may be traced from grounded battery, winding of the power magnet of sequence switch 400, upper right contact of sequence switch spring 413, left armature and back contact of relay 407, lower left contact of sequence switch spring 410, right armature and front contact of relay 406 to ground for rotating this sequence switch out of position 12 and into position 13. In position 13, a circuit extends from grounded battery, through the winding of the power magnet of sequence switch 400, lower contacts of sequence switch spring 411, right armature and front contact of relay 406 to ground, rotating this sequence switch out of position 13 and into position 14. In position 14 the energizing circuit for magnet 400 extends through the winding of the magnet, upper right contact of sequence switch spring 413, left armature and back contact of relay 407, upper contact of sequence switch spring 410 to ground. The sequence switch is thus rotated to position 15. A circuit now extends from grounded battery, upper right contact of sequence switch spring 416, resistances 424 and 423, lower contacts of sequence switch spring 420, brush 437, terminal 427, conductor 521, brush 510 and its associated normal contact, windings of relay 502, to ground. Relay 502 is energized in this circuit. The idle condition of the line is indicated to the test man by the steady illumination of lamp 227 which, it will be remembered was lighted upon the operation of relay 219. Key 243 is then operated, completing a circuit from grounded battery, right armature and back contact of relay 236, lamp 250, operated contact of key 243 to ground through the winding of relay 246. The energization of relay 130

246 places relay 237 across the tip and ring conductors 242 and 266, in a circuit which may be traced from grounded battery, right winding of relay 501, innermost lower armature and back contact of relay 502, conductor 503, terminal 428, brush 438, upper contacts of sequence switch spring 421, rings of jack 453 and plug 234, ring conductor of patching cord 233, rings of plug 232 and 10 jack 231, conductor 271, operated contact of key 243, winding of relay 237, operated contact of key 243, right armature and front contact of relay 246, conductor 259, contact 19 of the arc served by brush 206, conductor 268, left armature and front contact of relay 221, conductor 242, tips of jack 231 and plug 232, tip conductor of patching cord 233, tips of plug 234 and jack 453, lower contacts of sequence switch spring 422, brush 20 439, terminal 429, conductor 504, upper armature and back contact of cut-off relay 502 to ground. This circuit does not become effective since it will be remembered that relay 502 is energized. The test man may, 25 at will, ground test terminal 427 whereby relay 502 is shunted and the above traced circuit is completed for energizing relay 237. Relay 501, however, does not receive sufficient current through its right winding 30 to energize. The energization of relay 237 indicates that brushes 437, 438 and 439 are connected with terminals 427, 428 and 429, respectively, in the following manner. A circuit is completed from grounded battery, 35 winding of relay 239, to ground at the armature and front contact of relay 237. Relay 239 is energized causing in turn the lighting of lamp 249 from grounded battery, lamp 249, operated contact of key 243 to ground at the inner left armature and front contact of relay 239 as an indication that the test has been successfully completed. The test man then operates disconnect key 421, and withdraws plug 232 from jack 40 231 and plug 234 from jack 453. The circuit of Fig. 2 is then restored to normal in the same manner as described for the preceding test. As soon as plug 234 is withdrawn from jack 453, the holding circuit 45 for relay 406 is opened and this relay de-energizes. A circuit may then be traced from grounded battery, left winding of relay 407, upper contacts of sequence switch spring 411 to ground at the right armature and back contact of relay 406. Relay 407 is energized, in turn completing a circuit from grounded battery, winding of the power magnet of sequence switch 400, lower right contact of sequence switch spring 413, 50 left armature and front contact of relay 407, upper contact of sequence switch spring 410 to ground for rotating this sequence switch out of position 15 and into position 16. As sequence switch 400 leaves position 15½ the 55 energizing circuit of relay 407 is opened and

this relay deenergizes; completing a circuit from grounded battery, winding of the power magnet of sequence switch 400, upper right contact of sequence switch spring 413, left armature and back contact of relay 407 70 to ground at the upper contact of sequence switch spring 410, for rotating the sequence switch to position 17. In position 17 the energizing circuit for magnet 400 may be traced through the winding of the magnet, 75 lower right and upper left contacts of sequence switch spring 411 to ground at the right armature and back contact of relay 406. Sequence switch 400 is thus rotated to position 18. In position 18 a circuit may be traced from grounded battery, winding of downdrive magnet 401, lower contact of sequence switch spring 426, upper right contact of sequence switch spring 417, upper left contact of sequence switch spring 419 80 to ground. The final selector switch elevator is driven in a downward direction under the control of magnet 401. When brush 432 engages commutator segment 436 its motion is arrested, and a circuit completed from grounded battery, upper left contact of sequence switch spring 413, commutator segment 436, brush 432, upper left contact of sequence switch spring 419, to ground. Sequence switch 400 is rotated out of position 85 18 into its normal position 1, deenergizing downdrive magnet 401. This completes the brush continuity test on the final selector circuit. 90

Test for tip and sleeve crosses.

100

It sometimes happens that the tip and sleeve conductors of a selector circuit inadvertently come into contact with each other or are crossed by a piece of solder or other metal. The result of such a cross may obstruct the service upon a number of switches and cause a pile-up condition. The test for this condition will now be described. Keys 133, 141, 159 and 160 are operated in Fig. 1 105 to direct the selector to a test line, represented by terminals 442, 441, and 440. Plug 448 is then inserted in jack 445, plug 446 is inserted in jack 272, plug 234 is inserted in jack 453 and plug 232 is inserted in jack 231. Keys 208, 240, 256 and 238 are then 110 operated. The circuit then functions in the same manner as described for the brush continuity test of the final selector with the exception that when the final selector switch elevator shown in Fig. 4, comes to rest on terminals 442, 441 and 440, a busy condition on that line is not encountered and sequence switch 400 comes to rest in position 15 as described for the brush continuity test of the final selector circuit. With the brush assembly of the switch associated with magnet 200 in position 19 and sequence switch 400 in position 15, the test proceeds as described below. 115

120

125

130

Referring to Fig. 4, a circuit may be traced from grounded battery, upper right contact of sequence switch spring 416, resistances 424 and 423, lower contacts of sequence switch spring 420, brush 437, terminal 440, sleeve of jack 445 and of plug 448, sleeve conductor of patching cord 447, sleeve of plug 446 and of jack 272, operated contact of key 238, left winding of relay 236 to ground for energizing relay 236. It will be recalled when brush 205 stepped to contact 19, relay 219 was energized, in turn causing the energization of relay 210. Relay 237 is then energized in a circuit from ground, left armature and front contact of relay 210, normal contact of key 243, winding of relay 237, normal contact of key 243, operated contact of key 238 to grounded battery at the right armature and front contact of relay 236. The energization of relay 237 causes the energization of relay 239 in a circuit extending from grounded battery, winding of relay 239 to ground at the armature and front contact of relay 237. Relay 239, upon energizing, provides a holding circuit for relay 237 extending from grounded battery, right armature and front contact of relay 239, normal contact of key 243, winding of relay 237, normal contact of key 243 to ground at the left armature and front contact of relay 210. This holding circuit becomes effective for maintaining relay 237 energized upon the release of relay 236. If the tip and sleeve of the final selector circuit are crossed, a circuit may be traced from ground, inner left armature and front contact of relay 239, normal contact of key 243, left armature and back contact of relay 246, conductor 242, tip of jack 231 and of plug 232, tip conductor of patching cord 233, tip of plug 234 and of jack 453, lower contacts of sequence switch spring 422, brush 439, terminal 442, sleeve of jack 445 and of plug 448, sleeve conductor of patching cord 447, sleeve of plug 446 and jack 272, operated contact of key 238, through the left winding of relay 236 to ground. The left winding of relay 236 is now connected to ground on both sides and this relay is deenergized. A circuit may then be traced from grounded battery, resistance 222, outer right armature and front contact of relay 210, left armature and back contact of relay 236, lamp 227, armature and back contact of relay 218, left armature and front contact of relay 210, to ground, relighting lamp 227. A circuit also extends from grounded battery, right armature and back contact of relay 236, lamp 250, normal contact of key 243, outer left armature and front contact of relay 239 to ground at the normal contact of key 241. Lamp 250 is lighted as an indication to the test man that the tip and sleeve of the final selector circuit are crossed. If the crossed condition does not exist, the circuit traced for shunting relay 236 is open and this relay remains energized. A circuit therefore extends from ground through interrupter 273, normal contact of key 241, ring of jack 272 and of plug 446, ring conductor of patching cord 447, rings of plug 448 and jack 445, terminal 441, brush 438, upper contacts of sequence switch spring 421, ring of jack 453 and of plug 234, ring conductor of patching cord 233, ring of plug 232, and of jack 231, conductor 266, right armature and front contact of relay 221, conductor 252, lamp 274, left armature and front contact of relay 236 outer right armature and front contact of relay 210, resistance 222, to grounded battery. Lamp 274 is caused to flash in response to interrupter 273, as an indication to the test man that a crossed condition does not exist.

The circuits are now restored to normal in an obvious manner upon the withdrawal of the plugs from their respective jacks and the restoration of all operated keys.

While the brush continuity test has been described for use in connection with the final and incoming selector circuit, it is apparent that with slight modifications it can also be applied to office selector circuits such as are shown in Fig. 3 of Patent 1,395,977, issued November 1, 1921, to F. A. Stearn, et al. However it is not thought necessary for a complete understanding of the invention to describe the test as applied to such selectors.

What is claimed is:

1. In a telephone exchange system in which sets of terminals to which are connected the lines and line apparatus associated with subscribers' stations are caused to be selected by means of brushes associated with selector switches, a testing device for testing said selector switches comprising means to direct the brushes of any one of said switches to engage a set of said terminals, and means for denoting that said brushes are in contact with said terminals.
2. In a telephone exchange system in which sets of terminals to which are connected the lines and line apparatus associated with subscribers' stations are caused to be selected by means of brushes associated with selector switches, a testing device for testing said selector switches comprising means to direct the brushes of any one of said switches to engage a set of said terminals, and a relay operative over a circuit extending through the contacts of said brushes with said terminals to control a signal as an indication that said brushes are in contact with said terminals.
3. In a telephone exchange system in which sets of terminals to which are connected lines to subscribers' stations and auxiliary apparatus are caused to be selected by means of brushes associated with selector switches, said auxiliary apparatus consisting

of a line relay and a cut-off relay, said line relay being normally operable, a testing device for testing said selector switches comprising means to direct the brushes of any 5 one of said switches to engage a set of terminals, and means operative over a circuit extending through the contacts of said brushes with said terminals, including said line relay but rendering said line relay inoperable, to control a signal as an indication that said brushes are in contact with said terminals.

4. A testing arrangement for testing automatic switches, said switches having brushes 15 to make contact with any of a plurality of sets of fixed terminals, subscribers' lines and associated apparatus connected to said terminals, means to direct an automatic switch to any one of said subscribers' lines to make 20 a continuity test of said brushes with said sets of terminals, and means to actuate a signal from current derived from certain of said line apparatus independent of the actuation of said line apparatus.

5. In a telephone exchange system in which a first selector is actuated to select a second selector which is thereupon actuated to select a wanted line, a testing device, means in said testing device to cause said 30 first selector to perform its normal functions to select said second selector, a test line artificially made busy, means to cause said second selector to select said test line, an interrupter circuit associated with said 35 second selector for transmitting a line busy indication, and means in said testing device responsive to said line busy indication for denoting that said test line has been properly selected.

6. In a telephone exchange system in which a first selector is actuated to select a second selector which is thereupon actuated to select a wanted line, a testing device, means in said testing device to cause said 45 first selector to perform its normal functions to select said second selector, a test line artificially made busy, means to cause said second selector to select said test line, an interrupter circuit associated with said 50 second selector for transmitting a line busy indication, and a relay operative from said interrupter circuit for controlling a signal as an indication that operative circuits have been established over the brushes of said first 55 selector.

7. In a telephone exchange system in which brushes associated with selector switches are caused to select sets of terminals, a testing device for testing said 60 switches, means for connecting said testing device with said switch, a test line extend-

ing from one of said sets of terminals to said testing device, a sender at said testing device for causing said brushes to select a set of terminals associated with said test 65 line, circuits extending from said testing device over the tip and sleeve conductors and brushes of said switch and over conductors of said test line back to said testing device, a relay at said testing device 70 normally operative over one of said circuits but shunted over the other of said circuits if the first circuit is grounded or said circuits are short-circuited at said switch, and a signal under the control of said relay 75 for indicating such condition.

8. In a telephone exchange system in which brushes associated with selector switches are caused to select sets of terminals, a testing device for testing said 80 switches, means for connecting said testing device with said switch, a test line extending from one of said sets of terminals to said testing device, a sender at said testing device for causing said brushes to select a set of terminals associated with said test line, circuits extending from said testing device over the tip and sleeve conductors and brushes of said switch and over conductors of said test line back to said testing 85 device, a relay at said testing device normally operative over one of said circuits and held operated if said circuit is free from ground or cross-connection to the other of said circuits at said switch, and a signal 90 under the control of said relay for indicating such condition.

9. In a testing system, a testing device for testing an automatic switch having a plurality of brush circuits, means to associate 100 said testing device with said automatic switch, a test line, means to associate said test line with said testing device, means to test a particular one of said brush circuits for ground falsely associated therewith, said brush circuit being normally not grounded and automatic means to indicate whether said particular brush circuit is normal or is falsely connected to ground.

10. In a testing system, a testing device for testing an automatic switch having a plurality of brush circuits, means to associate 105 said testing device with said automatic switch, a test line, means to associate said test line with said testing device, and automatic means to indicate if the tip and sleeve brush circuits of said switches are cross connected.

In witness whereof, I hereunto subscribe my name this 4th day of November A. D., 120 1923.

HARRY W. MacDOUGALL.
